UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed April 8, 1924. Serial No. 705,089.

My invention relates to mining machines.

An object of my invention is to provide an improved mining machine. Another object of my invention is to provide an improved mining machine of very compact construction especially adapted to use in low-vein work. A further and more specific object of my invention is to provide an improved mining machine having improved 10 motor fluid supply connections, improved cutting mechanism controlling mechanism, improved cutting mechanism swinging and positioning means, improved feed controlling mechanism, and an improved arrangement 15 for the feed operating member and guiding members for the flexible feeding member. These and other objects and advantages of my improvements will, however, hereinafter more fully appear.

20 In the accompanying drawings I have shown for purposes of illustration one embodiment which my invention may assume in practice.

In these drawings,—

25 Fig. 1 is a plan view, partially broken away to facilitate illustration, of a mining machine incorporating my improved mechanism, the cutter bar being illustrated in different operative positions.

30 Fig. 2 is a side elevation of the mining machine shown in Fig. 1, a part of the frame being broken away.

35 Fig. 3 is an enlarged plan view, partially in section, of the cutter bar carrying end 33 of the machine.

Fig. 4 is a longitudinal sectional view 40 taken substantially on line 4—4 of Fig. 3.

Fig. 5 is a transverse sectional view taken substantially on line 5—5 of Fig. 3.

45 Fig. 6 is a detail sectional view taken on line 6—6 of Fig. 3, showing a portion of my improved lubricating mechanism.

Fig. 7 is a detail sectional view taken substantially on line 7—7 of Fig. 4, showing the 43 bar locking mechanism.

Fig. 8 is an enlarged end elevation of the feeding end of the machine.

Fig. 9 is a vertical sectional view taken substantially on lines 9—9 of Figs. 1 and 8.

50 Fig. 10 is a detail sectional view of my improved cutter chain controlling mechanism.

Fig. 11 is a detail elevational view, partially in section, of the portion of the mechanism shown in Fig. 10.

Fig. 12 is a plan view of the portion of the feeding end of the machine, partially broken away to facilitate illustration.

Fig. 13 is a transverse sectional view taken substantially on line 13—13 of Fig. 12.

Figs. 14 and 15 are detail views of my improved feeding controlling mechanism.

Fig. 16 is a transverse section taken substantially on line 16—16 of Fig. 15.

In this illustrative form of my invention, 65 I have shown my improvements applied to an air-propelled flexibly fed mining machine of the same general type as that described and claimed in my co-pending application, Ser. No. 619,839, filed Feb. 19, 1923, the 70 mining machine, generally designated 1, being of the long wall type adapted to slide on its own bottom and having an elongated frame 2 presenting parallel plane surfaces 75 3 and 4 upon which the machine is selectively adapted to slide during cutting, that is, when the machine is being used as an under cutter or an over cutter, and carrying at one end a cutter bar 5 pivoted on a vertical axis 6 on the rear end of the machine frame. The mining machine is also herein adapted to be moved longitudinally along the face relative to a flexible feeding means of any suitable form, herein including a 80 flexible feeding member or chain 7 adapted to cooperate through improved mechanism, herein described, with a feed operating member or sprocket 8 rotatable on a longitudinally extending horizontal axis on the front end of the machine frame. Disposed 85 intermediate and suitably secured to the frame portions inclosing the feeding mechanism and the cutting mechanism is a pressure fluid actuated motor 9 comprising a 90 pair of parallel longitudinally extending double helical intermeshing rotors 10 and 11, of a well known form, to which pressure fluid is adapted to be supplied through an improved detachable connection 12 herein- 95 after described. The rotors 10 and 11 are 100 also provided with longitudinally extending shafts 13 and 14 suitably journaled within the casing of the motor and provided with reduced end portions 15 and 16 having keyed thereto identical but reversely disposed long 105 sleeved pinions 17 and 18, of which the pinion 17, disposed at the end of the reduced portion 15 on the shaft of the rotor 10, is held in position by keying and a suitable lock nut connection 19, while the pinion 18 110

is similarly fixed to the shaft of the rotor 11, the pinions 17 and 18 thus rotating in parallel but in longitudinally spaced transverse planes. Selectively cooperating with 5 these pinions 17 and 18 is an adjustable pinion 20 disposed on a longitudinally extending shaft 21 disposed between and parallel with the rotor shafts and suitably journaled within the machine frame. As illustrated, 10 this pinion 20 is provided with a clutch shipper ring 22 formed thereon adapted to be engaged by a horizontally disposed U-shaped clutch shipper 23 pivoted on a vertical axis 24 on the machine frame 15 and having improved controlling mechanism therefor.

This improved controlling mechanism comprises an operating member 25 having a transversely extending pin 26 adapted to 20 be grasped by the operator and which secures the operating member 25 to a cylindrical member 27 arranged within a bore 28 formed in the machine frame. This member 27 is provided with an axial internal 25 bore 29 in which a member 30 is disposed which is provided with an upstanding bifurcated portion 31 adapted to engage a vertically disposed pin 32 suitably carried by a portion 33 formed integral with the shipper 30 per member 23. The opposite side of the frame is provided with a bore 34, similar to the bore 28, in which a flanged bushing 35 is disposed and held in position therein by a radially expanding split ring 36. This 35 bushing member 35 is provided with a bore 37, similar to the bore 29, in which a cylindrical member 38 having an upstanding portion formed thereon is disposed, the member 38 and the member 30 being connected together by a transversely disposed horizontal rod 39. It will herein be noted that the member 27 is provided with an inclined slot or cam surface 40 which is adapted to engage a radially extending pin 41 suitably 40 secured to the member 30. It is obvious that by rotating the operating member 25 in a counter-clock-wise direction, the inclined surface of the slot or cam 40 will act on the pin 41 causing the member 30 to be moved inwardly and swing the shipper member 23 about its pivot 24, thereby causing the pinion 20 to engage the pinion 17 which in turn causes the shaft 21 to be rotated by the rotor 10. By rotating the member 25 in a clockwise direction the shipper 23 will be swung in an opposite direction thereby causing the pinion 20 to be released from the pinion 17 and to be engaged with the pinion 18, consequently causing the shaft 21 to be rotated 50 by the rotor 11 in a reverse direction. The member 38 is provided with a diametrically disposed bore 42 in which a spring pressed ball 43 is disposed adjusted by a suitable follower and which is adapted to engage an annular spaced grooves 44 formed in the walls 55

of the bore 37 and thereby position the shipper 23 in either of its operative positions or in its central position. Obviously by transposing the parts to the opposite side of the machine the clutch shipper 23 may be operated from the opposite side of the machine thereby enabling the clutch to be operated when the sides of the machine frame are selectively disposed adjacent a face. 70

Secured to the shaft 21 is a bevel pinion 45 which meshes with a bevel gear 46 suitably journaled on a vertical axis 47 and to which a spur pinion 48 is suitably secured, which in turn meshes with a spur pinion 49 suitably journaled coaxially with respect to the bar pivot 6 and with which a cutter chain sprocket 50 is rotatable, the latter being driven by one or the other of the rotors 10 and 11 in opposite directions as circumstances require, and cooperating with an endless cutter chain 50' adapted to be circulated about the cutter bar 5. 80

Pressure fluid is adapted to be admitted to the motor 9 through a hose connection 51, from any suitable source of supply, this hose connection being secured to the member 12 by means of a threaded connection 52, and communicating with a passage 53 formed in the member 12 and with a passage 54 formed in a substantially U-shaped manifold member 55, the passage 54 communicating with a longitudinally extending passage 56 which communicates with the inlet of the motor 9. As illustrated, the passage 54 is branched and communicates with the opposite side of the machine frame so that the connection 12 may be reversely disposed on the opposite side of the machine frame whenever desired. Herein it will also be noted that a cover plate 57 is attached by screws 58 over the unused side of the passage 54 through which the passage 53 would communicate, it being understood that the connection 12 is also suitably drilled to receive similar bolts 58. It is also to be understood that both branches of the passage 54 communicate with the passage 56 and consequently with the inlet of the motor. The member 12 is herein also provided with a chamber 59 which is adapted to be supplied with lubricant by means of the removable filler plug 60. Formed in the walls of this chamber is also a vertical bore 61 in which a valve 62 is disposed which is provided with vertically spaced ports 63 and 64 adapted to register with ports 65 and 66 formed in the member 12, and which is also provided with a manual controlling handle 67. Pressure fluid is thus adapted to pass from the passage 53 through the ports 65 and 63 forcing the oil from the chamber 59 through the ports 64 and 66 into the passage 54 which permits the pressure fluid to mix therewith to lubricate the moving parts of the motor and cooperating parts. When the connection 12 is transferred to the oppo- 90 95 100 105 110 115 120 125 130

site side of the machine, the valve 62 is removed and inserted in the bottom of the connection 12 while a plug corresponding to the plug 60 permits the filling of the oil chamber.

The cutter bar 5 is herein as usual adapted to be swung about its axis 6 by means of the flexible feeding member or chain 7. The cutter bar is provided with an upstanding boss 69 grooved at 70 to overlie, and if necessary to be supported on, a flanged portion 71 formed integral with the machine frame 2, to maintain the bar in the desired plane of swing. A rotatable locking pin 72 is also seated in a bore 73 formed in the boss 69 and is provided with a removable annular flange 74 on its lower end, seated in a larger bored out portion 75, formed in the bar 5, in such a manner as to prevent longitudinal separation of the pin 72 when the machine is disposed on the plane surface 4, as during over cutting, while permitting free rotation thereof. Herein it will be noted that the pin 72 is cut away or slotted, as at 76, transversely intermediate its ends in such a manner as to form a locking portion 77 adapted to be received in any one of a plurality of corresponding cut away portions 78, formed in the flange 71. When the pin is suitably rotated, these cut away portions 78, are herein so disposed on the flange 71 as to enable the bar to be manually locked in longitudinal and in opposite lateral positions. Moreover it will be noted that the pin 72 carries on its upper end a coaxially disposed pin 79 having a hexagon shaped portion 80 formed thereon so as to permit manual adjustment thereof. This pin is adapted to receive one end of a curved double ended hook 81 adapted to be connected to either free end of the flexible feed member 7, the construction being such that a pull upon the latter and the pin 72 will swing the cutter bar 5 about its pivot, the desired pull herein being obtained by operation of the feed operating member 8. Herein it will also be noted that I have provided improved means for positioning the locking pin 72 which comprises a grooved or cut away portion 82 formed in an annular flanged portion 83 on the upper end of the pin, the ends of which groove are adapted to engage an upstanding pin 84 carried by the boss 69 in its different positions, thereby preventing excessive rotation of the pin and the consequent release of the lock.

The opposite ends of the shafts 13 and 14 of the rotors 10 and 11 are provided with reduced portions 85 and 86, the portion 85 having a pinion 87 keyed thereto as at 88, said pinion being adapted to mesh with a gear 89 which drives, through mechanism which is disclosed in my co-pending application mentioned above, the feed operating member 8 in opposite directions at fast and

slow speeds. It will herein be noted that the pinion 87 may be removed from the portion 85 of the rotor shaft 13 and placed on the reduced portion 86 of the rotor shaft 14, thereby causing the gear 89 to be rotated in an opposite direction, consequently reversing the direction of the rotation of the feed operating member 8. A sleeve member 90 is also placed on the unused end of the rotor shaft.

In describing my improved feeding controlling mechanism it will be noted that the fast and slow speed mechanism for the feed operating member 8 is provided with a frictional controlling device, generally designated 91 and 92, these devices being adapted to be alternatively placed in operation by my improved shipper mechanism to be now described and thereby connecting the feed operating member with the slow or fast speed. Pivoted on vertical axes 93 and 94 are clutch shippers 95 and 96 of U-form provided with rollers 97 and 98 adapted to engage the disk-like outer surfaces of the clutch operating members 99 and 100 of the friction devices. Moreover, it will be noted that these clutch shippers are provided with extensions 101 and 102 extending radially into lateral apertures 103 and 104 formed in ring-like portions 105 and 106 carried within the machine frame. These extensions 101 and 102 are provided with rectangular shaped portions 107 and 108 which register with slots or grooves 109 and 110 formed in parallel slidingly engageable rods 111 and 112 suitably guided in the machine frame at its opposite ends as at 113. These rods are grooved or cut away at 114 and 115 to permit longitudinal movement thereof and are provided with annular semi-circular portions 116 and 117 which are provided with threads of opposite pitch with which an annular nut member 118, provided with both right and left hand internal threads, cooperates, this member being split and clamped thereto by bolt and nut connections as at 119 and provided at its outer end with an operating handle 120 carried on the front end of the machine frame. It will be observed that by rotating the handle 120 the threaded nut 118, engaging the threads formed on the rods 111 and 112, will cause the latter to move in opposite directions thereby swinging the shipper members 95 and 96 about their pivots in opposite directions and causing one of the friction mechanisms to be released while the other is applied and thereby preventing the application of two feeds, i. e. the fast and slow feed, simultaneously. Disposed adjacent the handle 120 and parallel thereto is also a handle 121 rotatable to control the pressure fluid supply to the inlet of the motor 9.

It will herein be noted that the feed operating member 8 is rotatable with a lon-

itudinally extending shaft 122 (see Fig. 9) suitably journaled in longitudinally spaced roller bearings 123 and 124 and to which shaft an internal gear 125 is keyed, as at 5 126, which is adapted to be driven by certain elements of the feeding mechanism as described in my co-pending application. As illustrated, a guiding member or sprocket 127 is mounted on a vertical axis, in the 10 form of a stud 128, closely adjacent the feed operating member 8 and slightly in the rear of the same and above the axis thereof, the sprocket 127 being disposed in such a 15 position that the feed chain 7, laterally passing off of the upper side of the feed sprocket 3, may pass around the outer side of the 20 guide 127. A similar guide sprocket 129 is similarly mounted on the opposite side of the feed operating member 8 in the same 25 general location. It will also be noted that adjacent each of these members 127 and 129, and herein in transverse horizontal alignment therewith, external or corner guides 130 and 131 are mounted, the same preferably 30 extending slightly beyond the lateral edges of the machine frames and slightly in the rear of the members 127 and 129 as shown. It will also be noted that guide sprockets 132, 133, 134 and 135, similar to 35 the guide sprockets 127, 129, 130 and 131, are disposed coaxially therewith in a transverse horizontal plane below the axis of the feed operating member 8, the feed operating member being disposed adjacent the front 40 end of the machine frame. Thus due to this arrangement and location of the feed operating and guiding elements free access may be readily had to the feed operating and 45 guiding elements to permit the change of the arrangement of the flexible feeding member 7 relative thereto with facility as desired.

While I have in this application specifically described one form which my invention 50 may assume in practice, it will be understood that this form of the same is shown for purposes of illustration and that the invention may be modified and embodied in various other forms without departing from its spirit or the scope of the appended claims.

What I claim as new and desire to secure by Letters Patent is—

1. In a mining machine, a frame having a 55 feed operating member thereon adapted to cooperate with a flexible feeding element and rotatable on an axis extending longitudinally of the machine, and cooperating guiding mechanism including a plurality of guiding members disposed on upstanding axes on 60 each side of and in horizontal planes above and below the axis of said feed operating member whereby a flexible feeding element may be reeved in operative engagement with said feed operating member and with guid-

ing members on opposite sides thereof simultaneously. 65

2. In a mining machine, a frame having a feed operating member thereon adapted to cooperate with a flexible feeding element and rotatable on an axis extending longitudinally 70 of the machine, and cooperating guiding mechanism including a plurality of coaxial guiding members disposed on upstanding axes on each side of and in horizontal planes above and below the axis of said feed operating member whereby a flexible feeding element may be reeved in operative engagement with said feed operating member and with guiding members on opposite sides thereof simultaneously. 75

3. In a mining machine, a frame having a feed operating member rotatable on an axis extending longitudinally of the machine, and guiding mechanism at each side of said feed operating member disposed on vertical axes and in horizontal planes parallel to and above and below the axis of said feed operating member within the bounding limits of said frame. 80

4. In a mining machine, a frame having a feed operating member thereon adapted to cooperate with a flexible feeding element and rotatable on an axis extending longitudinally of the machine, and cooperating guiding mechanism including coaxially disposed 90 spaced guiding members disposed on vertical axes on each side of the axis of said feed operating member whereby a flexible feeding element may be reeved in operative engagement with said feed operating member and with guiding members at each side thereof simultaneously. 95

5. In a mining machine, a frame having a feed operating member thereon adapted to cooperate with a flexible feeding element and rotatable on an axis extending longitudinally of the machine, and cooperating guiding mechanism including a plurality of series of coaxially disposed spaced guiding members disposed in horizontal planes above and below the axis of said feed operating member whereby a flexible feeding element may be reeved in operative engagement with said feed operating member and with guiding members at each side thereof simultaneously. 100 110

6. In a mining machine, a frame having a feed operating member thereon adapted to cooperate with a flexible feeding element and rotatable on an axis extending longitudinally of the machine, and cooperating guiding mechanism including a plurality of series of spaced rotatable guiding members having their axes parallel and disposed in horizontal planes above and below the axis of said feed operating member and disposed in a vertical plane in the rear of the latter and wholly within the bounding limits of the frame whereby a flexible feeding element 120 125

- may be received in operative engagement with said feed operating member and with guiding members at each side thereof simultaneously.
- 5 7. A mining machine having a swingable cutter chain carrying cutter bar, a flexible feeding means, and rotatable bar locking means connected to said flexible means and including means adapted to engage a relatively stationary abutment for limiting the rotation of said locking means.
- 15 8. A mining machine having a swingable cutter bar and a flexible feeding member, and a rotatable bar locking means connected to said member and including means adapted to engage a relatively stationary abutment for limiting the rotation of said locking means in either direction.
- 20 9. A mining machine having a swingable cutter bar and a flexible feeding member, and bar locking means adapted to be connected to said member and including limiting means carried by said bar with which a portion of said bar locking means engages to limit locking and unlocking movements thereof.
- 25 10. A mining machine having a swingable cutter bar and a flexible feeding member, and bar locking means including a rotatable pin having abutments thereon and adapted to be connected to said flexible member and including limiting means carried by said bar with which said abutments are adapted to engage.
- 30 11. A mining machine having a swingable cutter bar and a flexible feeding member, a bar locking means including a rotatable pin having a cut away portion and adapted to be connected to said flexible member and limiting means for said pin carried by said bar with which the ends of said cut away portion are adapted to engage.
- 35 12. A mining machine having a swinging cutter bar, flexible feeding means, rotatable bar locking means having means adapted to engage a relatively stationary abutment for limiting the rotation thereof, a hook engageable with said bar locking means, and means for connecting said flexible feeding means to said hook.
- 40 13. In a mining machine, a feeding mechanism including a feed operating member, a plurality of friction clutch elements controlling the rotation of said feed operating member, and means for alternately applying said clutches including parallel rods and a common operating element therefor for moving the same simultaneously oppositely longitudinally.
- 45 14. In a mining machine, a feeding mechanism including a feed operating member, a plurality of friction clutches controlling the rotation of said feed operating member, and means for applying said clutches including a common rotatable operating element and operating members individual to each clutch
- each directly engaged by said common rotatable operating element.
- 50 15. In a mining machine, a feeding mechanism including a plurality of clutch elements, and means for alternately applying said clutch elements including shipper mechanism, a plurality of rods cooperating therewith having threaded portions formed thereon, and a common operating means for said rods engageable with the threaded portions of each rod.
- 55 16. In a mining machine, a feeding mechanism including a plurality of clutch elements, and means for applying said clutch elements including parallel rods having threaded portions formed thereon and a split nut connection cooperating with said threaded portions.
- 60 17. In a mining machine, a feeding mechanism including a plurality of clutch elements, and means for applying said clutches including parallel rods and common operating means for simultaneously moving said rods in opposite directions longitudinally.
- 65 18. In a mining machine including a driving motor of the intermeshing toothed rotor type, feeding mechanism therefor including a feed operating member rotatable on an axis extending longitudinally of the machine, and transposable means whereby said feed operating member may be driven from either of said rotors.
- 70 19. In a mining machine including a driving motor of the intermeshing rotor type, feeding mechanism therefor including a feed operating member rotatable on an axis extending longitudinally of the mining machine, and means connectable to said rotors whereby said feed operating member may be driven in opposite directions at the same speed.
- 75 20. In a mining machine including a driving motor of the intermeshing helical rotor type, feeding mechanism therefor including a feed operating member rotatable on an axis extending longitudinally of the machine, and transposable means connectable to said rotors whereby said feed operating member may be driven in opposite directions at the same speed.
- 80 21. In a mining machine, a cutter chain driving member, and controlling mechanism therefor including a clutch, rotatable cam means for operating said clutch whose throw is at approximately right angles to the direction of clutch movement and parallel to its own axis of rotation, and clutch moving means including an element movable rectilinearly by said cam means.
- 85 22. In a mining machine, a cutter chain driving member, and controlling mechanism therefor including a clutch, and means for operating said clutch including a bell crank and cam operated means engageable therewith including an element movable recti-
- 90 95 100 105 110 115 120 125 130

linearly and engaging the bell crank and a cam for moving said element.

23. In a mining machine, a cutter chain driving element, and controlling mechanism therefor including a clutch, helical cam means for operating said clutch, and means for holding said cam operating means in different operative positions.

24. In a mining machine, a cutter chain driving sprocket, and controlling mechanism therefor including a clutch, helical cam means for operating said clutch and yieldable means for holding said cam operating means in different operative positions. 10

In testimony whereof I affix my signature.
MORRIS P. HOLMES.
